(73) Assignee: **Cochlear Limited**, Macquarie University (AU)

(57) **CLAIM**
The ornamental design for an external component of a hearing prosthesis, as shown and described.

(**) Term: **15 Years**

DESCRIPTION

(21) Appl. No.: **29/531,479**

FIG. 1 is a perspective view of a first embodiment of an external component of hearing prosthesis;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is bottom view thereof;
FIG. 8 is a perspective view of a second embodiment of the external component of hearing prosthesis;
FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is bottom view thereof.

(22) Filed: **Jun. 26, 2015**

The broken lines showing in the drawing views are for the purpose of illustrating portions of the external component of a hearing prosthesis that form no part of the claimed design.
